UNITED STATES PATENT OFFICE.

MORGAN LEWIS, OF SAWTELLE, CALIFORNIA; ANN LEWIS ADMINISTRATRIX OF SAID
MORGAN LEWIS, DECEASED.

UNDERREAMER FOR OIL-WELLS AND THE LIKE.

1,175,911.

Specification of Letters Patent. Patented Mar. 14, 1916.

Application filed February 26, 1915. Serial No. 12,228.

To all whom it may concern:

Be it known that I, MORGAN LEWIS, a citizen of the United States, residing at Sawtelle, in the county of Los Angeles and State of California, have invented a new and useful Improvement in Underreamers for Oil-Wells and the like, of which the following is a specification.

My invention relates to well drilling tools and has for its object the provision of an underreamer adapted to be inserted in the well through the drive pipe or casing for reaming out the hole below the lower end of the casing to permit the casing to be lowered in the well from time to time as the drilling progresses. I am aware that patents have been granted upon devices for this purpose and that the articles are now in commercial use, but the primary object of my device is to improve the method of reaming out the well holes with the provision of a device capable of heavy duty and absolutely positive action. A source of trouble in some of the well known types of reamers consists in the failure of the springs by which they are held in tension when in use to guarantee a proper and reliable action at all times of the cutters, and further, inasmuch as most of the well known types are very complicated, a great deal of trouble is encountered in their operation, thus causing delays in the work and no little annoyance to the operators. In addition to the above features the work is not generally performed in a proper or satisfactory manner, and it is the object of my present invention to provide a tool free from the objectionable features above noted and capable of constant and satisfactory work under all conditions.

Other objects may appear in the description following.

Referring to the drawings in which similar characters of reference indicate the same parts throughout the several figures, Figure 1 is an elevation of my reamer, partly shown in section in position in a well casing; Fig. 2 is a sectional elevation of the same with the cutters expanded and the tool body and casing in section; Fig. 3 is a sectional elevation of Fig. 2 at right angles thereto; Fig. 4 is a sectional plan on the line 4-4, Fig. 2; Fig. 5 is a sectional plan on the line 5-5, Fig. 2; Fig. 6 is a view of a wrench for contracting the cutters when it is desired to lower them in the casing.

The exterior of the tool body 1 is of the usual form but the lower end thereof has a socket 2 formed therein, extending upwardly for a convenient distance and a pocket 3 is formed in the upper end of the socket. A pair of cutters 4 and 5, exactly alike in form and function, have the stems 6 and 7 extending upwardly in the socket 2 of the body and the cutters 8 and 9 at their lower ends. The form of the cutters is best shown in Fig. 2. The cutters are pivotally mounted on a bolt 10 having a head 11 and a square nut 12 on the opposite end from the head, and this bolt is slidable vertically in the body 1 by means of slots 13 which are countersunk to receive the head and nut of the bolt. The cutting portions 8 and 9 of the cutters 4 and 5 are of semi-circular cross section and conform to the periphery of the body 1, shoulders 14 and 15 being provided below the end of the body and the stems 6 and 7 being tapered from the approximate size of the socket 2 on the axial line to the upper ends in order to provide sufficient clearance for the free movement of the stems when the cutting ends are contracted as shown in Fig. 1. Diagonal grooves 16 and 17 are formed in the side of the stems 6 and 7 in which is placed the ends 18 and 19 of the spring 20, the central portion of this spring being bent around the bolt 10 and the lower ends of the grooves conforming to the shape of the spring.

The spring 20 serves to hold the upper ends of the stems in contact and the cutting ends expanded and when the cutting ends rest upon the bottom of the well or any firm surface, the upper ends of the stems are forced upwardly into the pocket 3 at the end of the socket 2, where they will remain firmly locked in position until the pressure on the body is released, or until the cutters are pulled outwardly from the socket. The stroke of the body in the reaming operation forces the shoulders 14 and 15 against the lower end of the body and thus presents an unyielding surface to take the shock of the stroke.

When the tool is to be inserted in the casing for the purpose of reaming out the hole, the form of wrench shown in Fig. 6, or any other suitable form may be used to contract the cutters sufficiently to enter the casing, the ring portion 21 of the wrench being forced downwardly over the body 1

and over the cutters by grasping the handle 22, and the cutters placed in the upper end of the casing, where they may be lowered in the casing in the usual manner. As shown in Fig. 1, when the tool is in the casing, the lower ends of the cutters frictionally engage the wall of the casing 23 until the bottom thereof has been reached, when they will automatically expand to the limit of their movement, in which case the distance across the cutting points will exceed slightly the diameter of the casing, so that the latter may be easily lowered into the hole thus produced.

In order to contract the cutters, it is necessary that the upper ends be withdrawn from the pocket 3, and this is accomplished by the movement of the cutters downwardly in the pocket 2 which is permitted by the movement of the bolts 10 in the slots 13, the upper ends of the cutters in such case assuming positions against the walls of the pocket 2, as shown in Fig. 1.

It frequently occurs, when the reamer is being inserted in the casing that the cutters 8 and 9 which are contracted and frictionally engage the wall of the casing in their descent in the well, will slightly expand beyond the inner wall of the casing at a joint and stick against the upper end of a casing section. In order to prevent such an occurrence in the use of my device, I therefore provide grooves 24 on the rounded outer portions of the cutters 9 and 10, in which before the tool is inserted in the casing, a wire 25 may be placed and twisted one or more turns at the ends to hold the cutter points contracted sufficiently so that they may not touch the end of the casing as described. This wire will not in any way prevent or hinder the tool being lowered in the casing and when the bottom of the well is reached one or two strokes of the tool will sufficiently expand the cutters to break the wire and render the cutters ready for service.

It is to be observed that my device consists of only three main parts, the body 1 and the cutters 4 and 5, and the latter may be readily removed from the body for the purpose of sharpening by turning the bolt 10 with a screw driver and thus releasing it from the nut 12 which is held from turning by making the countersunk portion of the slot in which it is seated square as shown.

It is obvious from the consideration of the foregoing description of the operation and structure of my invention, that a thoroughly practical and positive reamer is hereby provided; the device is free from small and delicate parts, the structure of the entire mechanism is massive and capable of the

heaviest duty, the absence of springs to accomplish the drilling enhances its efficiency, and a great economy may be effected by its use.

Having thus described my invention, what I claim as new and desire Letters Patent for, is:—

1. An underreamer for oil wells and the like including an integral recessed tool body having a pocket at the upper end thereof, a pair of expandable cutters movable pivotally and slidably therewithin on a common axis, and peripheral springs seated in and extending around the axis of the cutters for holding the cutters normally expanded beyond the peripheral line of the well casing, the upper ends of the cutters being seated in said pocket when the cutters are so expanded.

2. An underreamer for oil wells and the like including an integral recessed tool body having a pair of commonly held cutters within and movable longitudinally and pivotally in the body together with their axis and means in the periphery of the cutters midway of their length for holding the cutters normally expanded and means within the body for locking the cutters in their expanded relation.

3. An underreamer for oil wells and the like including an integral tool body having a socket therewithin and a pocket at the end of the socket, a pair of cutters movable pivotally on a common axis and longitudinally in the body with their axis, the stems of the cutters extending into and seating in said pocket and the cutters extending below the body, and common means carried by and seated in the periphery of said cutters for holding the cutters normally expanded.

4. An underreamer for oil wells and the like including an integral tool body having a socket formed therein and a pocket at the closed end of said socket, a pair of like cutters arranged on a common movable axis within said socket with stems extending into the socket and cutting portions extending therefrom, said cutters being fulcrumed midway between said stems and cutting portions, and springs looped around the cutter axes at the center and extending diagonally of the cutters and upwardly into the socket seated in said cutters for holding the cutters normally expanded beyond the peripheral line of the well casing, said stems being adapted to seat in said pocket for locking the cutters in their expanded state.

MORGAN LEWIS.
